UNITED STATES PATENT OFFICE.

RALPH M. JACKSON, OF LA HABRA, CALIFORNIA.

FUMIGATING APPLICATOR.

Application filed August 16, 1920. Serial No. 403,882.

To all whom it may concern:

Be it known that I, RALPH M. JACKSON, a citizen of the United States, residing at La Habra, in the county of Orange and State of California, have invented a new and useful Fumigating Applicator, of which the following is a specification.

My invention relates to measuring devices and gasifiers for applying liquid gases for fumigating purposes under covered trees.

As one familiar with the fumigation of citrus trees, I am not aware of a similar device having the measuring means under the tree and cover when in operation, nor with the measuring means operating with a uniform stroke, as will be found the basic principles of this device.

As far as I know in devices of this character, prior to my invention the measurement of dosage was controlled by means of a graduated gauge, graduated in single ounces or units and permitting the stroke of the actuating member to vary with the number of units measured, instead of accomplishing the measurement with a uniform stroke and a fixed plurality of ounces or units per stroke, the means employed in my device and which has advantages over the old means, especially for night work.

Safety in operation, uniformity of dosage, simplicity of operation and construction and light weight construction are among the objects of this invention. Other objects will appear from the following description and the claims.

Referring to the drawings generally;

Fig. 1 is a perspective side elevation of the complete applicator.

Fig. 2 is an enlarged sectional detail of the measuring means and gasifier taken on the line 2—2 of Fig. 3.

Fig. 3 is an enlarged top plan view of the measuring means and gasifier.

Fig. 4 is a fragmentary top plan view of the supply tank and a detail of the measure control attached thereto.

Fig. 5 is a side elevation showing the applicator in use in connection with a covered tree.

The device comprises a supply tank 1 having the filler cap 2 and the valve 3 arranged in the pipe 5 leading to the auxiliary tank 4. This auxiliary tank is arranged at an appreciable distance at one

side of tank 1, and extends but a slight distance upwardly from the base of the device. By this arrangement the auxiliary tank and the mechanism associated therewith including the vaporizing apparatus, 60 may be inserted beneath the covering over the tree to be fumigated, while permitting the tank 1, and the operating and controlling mechanism associated therewith to be positioned outside of the tree cover where 65 the operator may readily reach the same.

Leakage in a device of this character is most likely to occur at the stuffing boxes and joints forming a part of the measuring and vaporizing mechanism, and by placing 70 this mechanism beneath the tree cover, any poisonous fumes escaping from the mechanism when in operation and subjected to pressure, will be prevented from reaching the operator.

The auxiliary tank 4 extends across the measuring and vaporizing mechanism, and a pump cylinder 9 is arranged in the auxiliary tank at one side of the upper portion thereof, so that the auxiliary tank 80 may extend upwardly in horizontal alignment with the pump cylinder and beyond the same. The pipe 5 communicates with the auxiliary tank in vertical alignment with the portion of the latter, which extends upwardly in back of cylinder 9. A valve mechanism 6 regulates the supply from pipe 5 to auxiliary tank 4, and controls the free flow of fluid to the vaporizing nozzles 10 and 11, said valve being actuated by a float 90 7 positioned in the portion of the auxiliary tank beyond cylinder 9.

A pump plunger 8 is provided in cylinder 9, and the action of said pump plunger is adapted to draw liquid from auxiliary 95 tank 4 to vaporizing nozzles 10 and 11 arranged above the pump.

The pump is so arranged that its plunger reciprocates horizontally, and aside from other obvious advantages, with this construction the distance to which the measuring and vaporizing mechanism extends upwardly from the base of the device is materially lessened.

An operating lever 12 is fulcrumed at 105 14 on the side of supply tank 1, and the upper end of the lever is provided with a handle 14a. A connecting rod 13 is provided between the opposite end of the operating lever and the pump. The lever 12 110

is adapted to be swung back and forth through a guide way 15, and adjusting screws 16 and 17 are provided at the respective ends of the guideway so as to limit 5 the stroke of lever 12.

A suitable handle 18 may be provided for carrying the entire device.

The supply tank 1, is filled with liquid gas after removing the filler cap 2, then 10 the filler cap is replaced and the valve 3 is opened permitting the liquid gas to flow into the auxiliary tank and float chamber 4, through the pipe 5 and float valve 6, the float 7 controlling the flow of liquid. 15 The measuring means and gasifier is placed under the edge of and inside of the cover, leaving the operating means and the supply tank outside of the cover. The liquid is pumped and measured from the auxiliary 20 tank by the stroke of the pump plunger 8, in the pump cylinder 9, to the vaporizing nozzles 10 and 11, and thence delivered under the tree and cover. The operating 25 lever with its fulcrum at 14 is controlled by the measure controller 15, which gauges the stroke and dosage. The stroke and dosage 30 is adjusted to the requirements and accuracy by screwing back or forth the adjusting screws 16 and 17.

As the customary minimum dosage is two ounces it is preferable to employ a small double acting pump with a stroke adjusted to measure two ounces each way uniformly, and pump and measure the dosage from two 35 ounces up, according to requirements. It is to be understood however, that a construction of greater capacity than two ounces per stroke, may be employed if so desired. In case of odd ounces the operating lever is 40 sprung into and stopped by the notch 19, which is midway of the stroke, accomplishing the measurement of one ounce. For example, if the requirements call for seven ounces the operator would make three and 45 one-half strokes of the operating lever, the operating lever would then start the next application in the center of the stroke and should the next application require nine ounces, the operator would make a half 50 stroke back or forth followed by four full strokes. The operating lever would then be left to start again on a full stroke.

The pump cylinder is preferably enclosed in the auxiliary tank and submerged in the 55 liquid. This is for the purpose of keeping the pump cylinder an equal temperature with the sensitive liquid gas material employed, which is quickly affected by slight change of temperature.

The supply tank is vented through the tubing 20 and the auxiliary tank is vented 60 through the perforation 21.

With the measuring means under the cover when in operation, danger to the operator of deadly fumes leaking from stuffing 65

boxes or joints subjected to pressure is eliminated.

More uniformity of dosage is accomplished with this construction due to the material being delivered directly from the 70 measuring means to the vaporizing nozzles.

Having thus described my invention, I claim:

1. In combination with a cover, a fumigating applicator including a supply receptacle for fumigating material, measuring mechanism and vaporizing means for measuring and vaporizing the material, said measuring mechanism and vaporizing means being associated with the said receptacle and supplied with the material therefrom, the said measuring mechanism comprising a measure controlling member and an actuating member controlled thereby, said actuating member functioning outside of said cover, 75 a connecting member projecting laterally from the actuating member, and a measuring member connected with the actuating member by the said connecting member, the said measuring member received beneath 80 and functioning inside of the cover.

2. The combination with a covered tree, of a fumigating applicator including a supply receptacle for fumigating material, and measuring mechanism and vaporizing means 95 for measuring and vaporizing the material, said measuring mechanism and vaporizing means being associated with the said receptacle and supplied with the material therefrom, the said measuring mechanism comprising a measure controlling member and an actuating member controlled thereby, said actuating member functioning outside of said cover, a connecting member projecting laterally from the actuating member, and a measuring member connected with the actuating member by said connecting member, the said measuring member received beneath and functioning inside of the 100 cover of said tree.

3. A fumigating applicator including a receiving tank for the fumigating material, a reciprocating measuring pump for drawing the material from said tank, and vaporizing nozzles for discharging the material, 105 communicating with the respective ends of said pump and supplied therefrom.

4. A fumigating applicator including a supply tank for the fumigating material, an auxiliary tank supplied therefrom with the 110 fumigating material, measuring means at said auxiliary tank for said fumigating material, and vaporizing nozzles for discharging the fumigating material positioned at the auxiliary tank and communicating with 115 the measuring means and supplied therefrom.

5. A fumigating applicator having vaporizing and measuring mechanism for the fumigating material and including a tank 130

- for said material, a pump cylinder within said tank and communicating therewith at its respective ends so as to receive said fumigating material, a reciprocating piston in said cylinder for pumping said material, and discharging nozzles cooperating with the respective ends of said pump and supplied therefrom with the fumigating material.
- 10 6. A fumigating applicator comprising a supply tank for fumigating fluid, an auxiliary tank, a fluid conductor connecting said tanks for supplying fluid to the auxiliary tank, vaporizing nozzles at said auxiliary tank, tank for discharging the fluid, a float in the auxiliary tank, a valve controlled thereby and regulating the flow of fluid into the auxiliary tank, means connected with the vaporizing nozzles for measuring the fluid 15 in proper dosage from the auxiliary tank, and a lever having an adjustable stroke for actuating the measuring means.
7. A fumigating applicator for trees including a supply receptacle for fumigating fluid, measuring and vaporizing mechanism 20 associated with the said receptacle for measuring and vaporizing dosage of said fluid, and automatic valve means for controlling the free flow of said fluid through the said 25 mechanism, the said measuring and vaporizing mechanism including measuring means, vaporizing means including vaporizing nozzle means, an actuating member for the said measuring means and vaporizing means, 30 and a measure controlling member for controlling the stroke of said actuating member, the said automatic valve means positioned 35 at the said nozzle means.
8. A fumigating applicator including a 40 containing receptacle for fumigating fluid, and measuring mechanism and vaporizing means associated with the said receptacle for measuring and vaporizing the fluid, the said measuring mechanism comprising a measure 45 controlling member an actuating member controlled thereby, and a measuring cylinder associated with the said actuating member and submerged in the fluid within
- the said receptacle for keeping the said cylinder at an equal temperature with the fluid. 50
9. A fumigating applicator including a containing receptacle for fumigating material, a measure controlling member, an actuating member controlled thereby, horizontally disposed measuring and discharge 55 mechanism for measuring and discharging fumigating material, said mechanism being actuated by the said actuating member and associated with the said containing receptacle and supplied with fumigating material 60 therefrom.
10. A fumigating applicator including a supply receptacle for fumigating fluid, vaporizing means for said fluid, a measuring pump immediately connected to said vaporizing means for forcing fluid from said receptacle directly to and discharging the same through said vaporizing means, the said pump having a predetermined discharge 65 at each normal stroke thereof, and means 70 remote from said vaporizing means for varying the length of stroke of said measuring pump.
11. A fumigating applicator including a supply receptacle for fumigating fluid, 75 vaporizing discharge nozzle means for vaporizing said fluid, a measuring pump connected at its inlet with said receptacle and immediately connected at its outlet with said nozzle means, said inlet connection including a fluid controlled float valve, said measuring pump having a predetermined fluid discharge at each normal stroke thereof and adapted to discharge a dose of fluid directly from said receptacle through said 80 nozzle means in intermittent expulsions of predetermined measurement, and means for varying the length of the stroke of said pump.
- In testimony whereof I hereunto affix my 85 signature in the presence of two witnesses.

RALPH M. JACKSON.
